DESCRIPTION

U.S. PATENT DOCUMENTS

FIG. 1 is a perspective view of a first handset showing my new design;

D502,456 S * 3/2005 Huang ..... D14/138 AA
D514,079 S * 1/2006 Lai ..... D14/138 AA
D515,536 S * 2/2006 Lee et al. ..... D14/138 AA
D523,836 S * 6/2006 Park ..... D14/138 AA
D524,786 S * 7/2006 Paradise et al. ..... D14/138 AA
D543,182 S * 5/2007 Lee et al. ..... D14/138 AA
D543,184 S * 5/2007 Moon et al. ..... D14/138 AA
D545,801 S * 7/2007 Joung ..... D14/138 AA
D546,316 S * 7/2007 Wu et al. ..... D14/138 AA
D546,802 S * 7/2007 Cho et al. ..... D14/138 AA
D556,170 S * 11/2007 Lee et al. ..... D14/138 AA
D562,282 S * 2/2008 Suk et al. ..... D14/138 AA
D569,824 S * 5/2008 Cobb et al. ..... D14/138 AA
D573,573 S * 7/2008 Jung et al. ..... D14/138 AA

FIG. 2 is a front view thereof;

FIG. 3 is a right side view thereof;

FIG. 4 is a left side view thereof;

FIG. 5 is a top view thereof;

FIG. 6 is a bottom view thereof; and,

FIG. 7 is a rear view thereof.

The broken lines shown throughout the views that are immediately adjacent to the shaded areas and define unshaded regions, represent the bounds of the claimed design, while any other broken lines are directed to environment and are for illustrative purposes only; the broken lines form no part of the claimed design.
